UNITED STATES PATENT OFFICE.

GEORGE P. McLAUGHLIN, OF SHICKSHINNY, PENNSYLVANIA.

STOP MECHANISM FOR SPINNING MACHINES.

Application filed April 16, 1923. Serial No. 632,435.

To all whom it may concern:

Be it known that I, GEORGE P. McLAUGHLIN, a citizen of the United States, residing at Shickshinny, in the county of Luzerne 5 and State of Pennsylvania, have invented certain new and useful Improvements in Stop Mechanisms for Spinning Machines; and I do declare the following to be a full, clear, and exact description of the invention, 10 such as will enable others skilled in the art to which it appertains to make and use the same.

My invention relates to improvements in stop mechanism for spinning machines and 15 has more particular reference to the Atwood, model 5-B machine. In machines of this and similar types, the threads extend from the bobbins through the eyes of drop wires before they pass around the usual feed rolls, 20 which draw said threads from the bobbins to be acted on by the usual spinning means. In case any of the threads break above the feed rolls, the drop wire with which the broken thread was previously engaged, acts 25 to automatically bring the stop motion into play, but no provision whatever is made for stopping the machine if all of the threads are broken by the spinning means, at a point between this means and the feed rolls, the 30 result being that the threads ball upon the feed rolls and must be cut off and wasted. It is the object of my invention to provide an extra drop wire having a novel association with the usual stop mechanism so as to 35 automatically actuate the latter in case all of the threads are broken in the manner mentioned, the extra drop wire being provided with an eye through which all of the threads pass after they leave the feed rolls 40 and before they reach the spinning means.

With the foregoing in view, the invention resides in the novel subject matter herein-after described and claimed, the descriptive matter being supplemented by the accompanying drawings.

Figure 1 is a front elevation showing a portion of the Atwood stop mechanism equipped with my improvement.

Figure 2 is a vertical sectional view as 50 indicated by line 2-2 of Fig. 1, showing the normal relation of parts.

Figure 3 is a duplicate of Fig. 2 with the exception that it illustrates the action of parts when all of the threads are broken.

Figure 4 is a horizontal sectional view 55 as indicated by line 4-4 of Fig. 2.

Figure 5 is a perspective view of the extra drop wire.

In the drawings above briefly described, the numeral 1 designates one of the usual 60 rails of an Atwood model B spinning machine. To this rail, the upper end of a frame 2 is bolted, said frame being of well known construction and having a vertical guide 3 in which the controlling rod 4 of the usual stop motion, is slidably received, 65 said rod being movable upwardly to throw the machine out of action. A latch lever 5 is fulcrumed at 6 on the frame 2 and co-acts with a dog 7 on the rod 4 to normally hold 70 the latter against upward movement. Fulcrumed between its ends to the lower end of the latch lever 5 is a horizontal lever 8 whose front end is formed by an open frame having front and rear side bars 9 and 10 respectively, said lever being so balanced that it normally assumes the position shown in Fig. 2. In case any of the threads break, 75 however the rearwardly extending arms 11 on the usual drop wires 12, fall onto the front bar 9 and thereby tilt the lever 8 to the position shown in Fig. 3. This action moves the rear end of the lever upwardly 80 into the path of an oscillating latch actuating device 13 with the result that this device pushes the entire lever forwardly and releases the latch lever 5 from engagement 85 with the rod 4. This rod is thus free (see Fig. 3) to move upwardly and actuate the well known stop motion. This action takes place in case any of the threads 14 break 90 above the feed rolls 15 which draw them from the usual bobbins above the drop wires 12. The threads however usually extend directly from the feed rolls to the spinning means (not shown) after being wound several times around said rolls and if the spinning means breaks all of the threads below these rolls, there is no provision made for stopping the latter, with 95 the result that a great deal of the silk or other thread is balled upon said rolls and must be cut off and totally wasted. My invention however overcomes this difficulty.

Upon the rod 16 which forms a pivotal mounting for the drop wires 12, I pivotally mount an extra, downwardly extending drop wire 17 having a porcelain eye 18 at 100

its lower end, the upper end of said wire 17 being formed with an eye 18^a through which a screw 18^b passes for attaching the wire to an upward extension 18^c on the front 5 end of a rearwardly extending, horizontally offset arm 19 positioned in the same plane with and of greater length than the arms 11. By reference to Figs. 2 and 3, it will be seen that all of the threads pass through 10 the eye 18 before extending to the spinning means from the feed rolls 15. As long as said spinning means is properly operating, the tension on the threads will hold the drop wire 17 in the position of Fig. 2 so that it 15 is clear of the frame of the lever 8. In case the threads are broken however, (see Fig. 3) the tension on them is released, with the result that the arm 19 falls upon the rear bar 10 of the lever 8 and rocks the latter into the path of the latch actuator 13. This actuator pushes the entire lever 8 forwardly and thereby releases the latch 5 from the rod 4, permitting the latter to act upon the stop motion and bring the machine to 20 a standstill. Thus, balling of the threads upon the feed rolls 15 is prevented and a great saving is effected. In the machines now on the market, this balling occurs so often that the feed rolls 15 are now being 25 manufactured with longitudinal grooves which facilitate the use of a knife or a pair of shears in cutting the threads therefrom, thereby saving as much time as possible and preventing scratching of the rolls by the cutting instrument. By the use of my invention however, there is no necessity for cutting the threads from the feed rolls since 30 they are never allowed to accumulate thereon.

40 Attention is here directed to the fact that the arm 19 falls upon the rear side bar 10 of the lever frame instead of upon the front bar 9 which co-acts with the arms 11. This is greatly advantageous since it does not 45 permit the drop wire 17 to swing forwardly to an objectionable extent. By reference to Fig. 3, it will be seen that if the arm 19 were allowed to co-act with the front bar 9, instead of the rear bar 10, the drop wire 17 50 would project forwardly from the machine to quite an extent. This would interfere with the operator and would be very objectionable.

55 My invention is extremely simple and inexpensive, yet it is obvious that the same is highly efficient and advantageous. While I prefer to use the exact details shown, it

is obvious that minor changes may be made and furthermore, that the invention may be adapted to other machines than that shown. 60

The present application is a continuation in part of my allowed U. S. application, Serial Number 491,472, filed August 11, 1921 and consequently receives benefit of that filing date. 65

I claim:

1. In a thread spinner, the combination of a frame having a vertical guide, a rod 70 slidable in said guide and movable to actuate a stop mechanism, a latch mounted on said frame for holding said rod normally against movement, a driven latch releasing device adjacent said latch, a lever fulcrumed to said latch and having its rear end normally clear of said releasing device, upwardly extending drop wires pivoted on said frame and having rearwardly extending arms, the front end of said lever having an open frame upon whose front bar 75 said arms are adapted to drop to rock the lever into operative relation with said latch releasing device when any thread breaks, and a downwardly extending drop wire pivoted on said first named frame co-axially with the first named drop wires, said downwardly extending drop wire having an eye 80 through which all of the threads are trained before passing to the spinning means, said downwardly extending drop wire being provided with a relatively long rearwardly extending arm adapted to fall onto the rear side bar of the lever frame to rock the lever 85 in case all threads are broken by the spinning means. 90

2. A stop mechanism operating device for 95 use in connection with a thread spinning and doubling machine, comprising a substantially L-shaped member for disposition co-axially with pivoted drop wires, said member having a short upright arm and a 100 relatively long horizontal arm and being formed at the juncture of said arms with a bearing opening, the short arm also being provided with an opening, said long arm being longer than the corresponding parts 105 of the existing drop wires, an upright wire having eyes at its ends, the lower eye being for reception of the strands, and a fastener passing through the upper eye into the aforesaid opening in said short arm. 110

In testimony whereof I have hereunto affixed my signature.

GEORGE P. McLAUGHLIN.
